United States Patent Office.

JOHN SMITH, OF EAST LIVERPOOL, OHIO.

Letters Patent No. 95,156, dated September 21, 1869; antedated May 26, 1869.

IMPROVED BUTTER-JAR.

The Schedule referred to in these Letters Patent and making part of the same.

To all whom it may concern:

Be it known that I, JOHN SMITH, of East Liverpool, in the county of Columbiana, and State of Ohio, have invented a new and useful Butter-Jar; and I do hereby declare the following to be a full, clear, and exact description of the same, reference being had to the accompanying drawings, which are made a part of this specification.

The object of this invention is to so construct the jar that it may be hermetically sealed, in a cheap and simple manner, in order to protect the contained butter against atmospheric influence. The butter is by this means preserved in a pure state, it not being liable to work or become rancid.

The jar and its cover are constructed of ordinary earthenware, both internally glazed.

Extending around the inside of its mouth, somewhat below the top, is a supporting-rim or flange, *a*, whose upper surface is concave, forming a continuous groove, to receive the down-turned edge of the lid or cover *b*, which rests upon said flange *a*.

The form of the cover and of the upper edge of the jar is such that when the cover is in place, it is circumscribed by a continuous gutter or channel *c*.

When the cover is in place, its top is somewhat below the plane of the top of the jar; and in carrying out my invention, I fill the space above, up to a flush line, as well as the gutter *c*, with plaster of Paris, or other substance, *d*, which will constitute an effective sealing-medium. I apply to the surface of this sealing-

substance, so as to entirely cover the same, a piece of adhesive paper or cloth, *e*, which serves to exclude the air from the jar in the event of the cracking of the lid.

It is obvious that the sealing-substance secures the lid in place upon the jar. The channel around the lid affords accommodation for a greater thickness or amount of material there than elsewhere, the effect of which is to more securely hold the lid at the edge, where its direct union with the top of the jar-body is established.

It is manifest that the mode of sealing the jar may be practised at little expense, and is attended with no difficulty.

Having thus described my invention,

What I claim as new, and desire to secure by Letters Patent, is—

A butter-jar, consisting of the earthenware body, and its internal-flanged rim *a*, which is arranged below the top of the body, the earthenware cover *b*, leaving a space, *c*, in combination with the sealing-substance, as set forth, and the auxiliary paper covering *e*, when all parts are constructed and adapted to operate together as described.

The above signed by me, this 12th day of May, 1869.

JOHN SMITH.
